UNITED STATES PATENT OFFICE.

HARRY P. DAVIS, OF PITTSBURG, PENNSYLVANIA, ASSIGNOR TO WESTINGHOUSE ELECTRIC & MANUFACTURING COMPANY, A CORPORATION OF PENNSYLVANIA.

STRAIN-INSULATOR.

No. 861,094.

Specification of Letters Patent.

Patented July 23, 1907.

Application filed June 4, 1906. Serial No. 320,135.

To all whom it may concern:

Be it known that I, HARRY P. DAVIS, a citizen of the United States, and a resident of Pittsburg, in the county of Allegheny and State of Pennsylvania, have invented 5 a new and useful Improvement in Strain-Insulators, of which the following is a specification.

My invention relates to strain insulators for electric lines and it has for its object to provide a device of the said class that shall be simple and compact in construction and shall be adapted for use with relatively high voltage electric lines.

In the construction of electric lines and particularly such lines as are adapted for railway trolley service, it is often necessary to utilize means for mechanically connecting and electrically separating two conductors or cables which are at widely different potentials, as is the case when one is electrically connected to the supply circuit and the other is connected to the ground.

The single figure of the accompanying drawing is a 20 sectional view of a strain insulator which is constructed in accordance with my present invention and is well adapted for the service above indicated.

Referring to the drawing, a rod or tube 1 of suitable material is provided with a sleeve 2, composed of compressed mica, paper and varnish or other suitable insulating composition which is adequate to resist strains occasioned by relatively high voltages. A head or enlargement 3 may be screw-threaded or otherwise formed or fastened upon one end of the rod 1 and a strain loop 4 30 may be attached to its opposite extremity. A metal tube 5 is provided with a cap 6 at one end having an opening 7, substantially concentric with the tube 5, through which the insulated rod 1 is thrust. A relatively short tube 8, of very hard insulating material 35 like or similar to that of which the tube 2 is formed, surrounds the latter at one end and is interposed between the head 3 and the cap 6. The thickness of the tube 8 is such that the outer surface of the head 3 is flush with that of the tube, and its length is such that 40 the head 3 is located substantially in the middle of the metal tube 5. The head 3 is insulated from the tube 5 by an insulating tube 9 the composition of which may be substantially like that of the sleeve 2 and the tube 8. Within the tube 9, and against the head 3, may be fitted 45 a tube 8^a of substantially the same material and dimensions as the tube 8. The space within the tube 8^a, between the collar 3 and its open end, may be filled with any suitable insulating material 8^b, which is a fluid when hot and which becomes solid and hard when cold. 50 The arrangement of parts is specially well adapted for withstanding mechanical strains, the tube 5 and the rod 1 being under tension, while the tube 8 is under compression. The structure will also withstand electrical strains occasioned by considerable differences in 55 potential, since the conducting parts which are insu-

lated from each other are directly separated by insulating tubes that are capable of resisting high voltage strains.

The end of the tube 5, opposite the cap 6, is provided with a cap 10 and a plunger 11 having a projection 12 which extends outwardly through a hole in the cap and upon which is screw-threaded a strain loop 13. The cap 6 is provided with a flange 14 and, as the tube 2 is shorter than the rod 1, a molded insulator 15 preferably surrounds the rod 1 between the flange 14 and the strain loop 4 in order to seal the tube 2. With the insulator hereinbefore described, I have found that the best results may be obtained by first assembling all the parts except the molded insulator 15, the cap 10, the plunger 11 and the strain loop 13, then pouring a hot liquid insulating compound, into the space above the head 3. When this is done and the whole tube structure is heated thoroughly so that the crevices and joints may be completely filled, the plunger 11 is inserted and a very heavy pressure is exerted between the cap 6 and the projecting end of the plunger. This pressure is retained by the cap 10 when it is screwed upon the end of the tube 5.

Finally, the insulator 15, which may be formed of any one of several well known compositions, will preferably be molded in position but may be separately formed and pressed upon the rod and sleeve. When the liquid compound within the tube 5 becomes cold and solid, a compact mass results which yields only an 35 inappreciable amount under tension.

It will be understood that the strain loop 4 and the strain cap 10 may be replaced by any convenient devices, by means of which a line conductor may be attached to opposite ends of the assembled insulator and that other variations in size and arrangement of details 40 may be effected within the scope of my invention.

I claim as my invention:

1. A strain insulator comprising a metal tube, a rod that projects into the tube and has an enlargement located substantially in the middle of the tube, insulating tubes interposed between the end walls of the metal tube and the ends of the enlargement, and a single insulating tubular lining for the metal tube.

2. A strain insulator comprising a rod having an enlargement at one end, a metal tube having detachable end caps through one of which the rod projects, an insulating tube surrounding the rod enlargement and extending through the metal tube from end to end and insulating material between the ends of the enlargement and the ends of the metal tube.

3. A strain insulator comprising a rod having a head at one end, a metal tube having an insulating lining into which the head may be forced, a cap on one end of the metal tube, a sleeve surrounding the rod, and a body of hard insulating material interposed between the head and the cap.

4. A strain insulator comprising a rod having an insulating sleeve fitted over it and an enlargement at one end, a metal tube, normally in tension, having a bore

- terially larger than the diameter of the enlargement, end caps one of which is fitted over the insulating sleeve, an insulating tube, normally in compression, which is located between said end cap and the rod enlargement, and means 5 for completely insulating the rod and collar from the metal tube and its end cap.
5. A strain insulator comprising a metal rod having an enlargement at one end, an insulating sleeve of considerable length fitted over the rod, an insulating tube fitted over the sleeve and flush with the outer surface of the enlargement, another insulating tube fitted over the rod enlargement and the tube having the same external diameter and extending material distances therefrom in both directions, a metal tube fitted over the insulating tubes, a metal cap screw-threaded upon one end of the metal tube against the corresponding ends of the insulating tubes, a cylindrical insulating block fitted into the outer insulating tube, and a strain cap screw-threaded upon the corresponding end of the metal tube.
10. 6. A strain insulator comprising a rod having a head at one end and a strain loop at the other end, a sleeve of insulating material surrounding the rod between the head and the loop, a metal tube into which said rod projects, said tube having caps screwed upon its ends, one of which 15 has a strain loop, and insulating material completely filling the space between the rod and the walls of the tube.
7. A strain insulator comprising a rod having a head at one end and a strain loop at the other end, a sleeve of insulating material between the head and the loop, a cap 20 fitted over the sleeve, a metal tube having one end screw-threaded into the cap and having a strain loop attached to its opposite end, a tube of hard insulating material between the head and the cap, a molded insulator which surrounds the sleeve between the strain loop and the cap, and insulating material filling the remaining space within the metal tube.
8. A strain insulator comprising a rod having a head at one end and a strain loop at the other end, a tube or 25 sleeve of insulating material between the head and the loop, a cap fitted over the sleeve, a metal tube screw-threaded into the cap, a tube of hard insulating material

between the head and the cap, a plunger fitted into the free end of the metal tube and having a screw-threaded projection, a second cap screw-threaded onto the metal tube and having a hole through which the plunger projection extends, a strain loop attached to the plunger projection, and insulating material that fills the remaining space in the metal tube.

9. A strain insulator comprising a rod having a head at one end and a strain loop at the other end, a sleeve of insulating material between the head and the loop, a cap 50 fitted over the sleeve, a metal tube screw-threaded into the cap, a tube of hard insulating material within the metal tube between the head and the cap, a plunger fitted into the free end of the metal tube and having a screw-threaded projection, a second cap screw-threaded upon the metal tube and having a hole through which the plunger projection extends, a strain loop attached to the plunger projection, a molded insulator which seals said sleeve and extends from the strain loop to the cap, and insulating 55 material that fills the remaining space within the metal tube.

10. A strain insulator comprising a metal tube having removable end caps, a rod located partially within and partially without said tube and having a head upon its 60 inner end, an insulating sleeve surrounding the rod and extending from its head nearly to its outer end, and solid insulating material filling the remaining space within the metal tube.

11. A strain insulator comprising a metal tube, a rod 70 that projects into the tube and has an enlargement located substantially in the middle of the tube, two insulating tubes the respective ends of each of which engage the enlargement and the corresponding end of the tube and an insulating tubular lining for the side walls of the tube 75 into which the enlargement is fitted.

In testimony whereof, I have hereunto subscribed my name this 26th day of May, 1906.
